US00D758058S

(12) **United States Design Patent**
Granger et al.

(10) **Patent No.:** **US D758,058 S**
(45) **Date of Patent:** **** Jun. 7, 2016**

(54) **HEEL CUP**

(71) Applicant: **Spenco Medical Corporation**, Waco, TX (US)

(72) Inventors: **David B. Granger**, Lorena, TX (US); **Jacob Martinez**, Temple, TX (US)

(73) Assignee: **Spenco Medical Corporation**, Waco, TX (US)

(**) Term: **15 Years**

(21) Appl. No.: **29/531,388**

(22) Filed: **Jun. 25, 2015**

(51) **LOC (10) Cl.** **02-04**

(52) **U.S. Cl.**

USPC **D2/961**

(58) **Field of Classification Search**

USPC ..... D2/896, 946, 947, 950, 951, 954, 955, D2/956, 961, 976; 36/83, 88, 91, 92, 93, 36/94, 95, 96, 97, 98, 136, 25 R, 28, 30 R, 36/32 R, 36 R, 43, 44, 71

(57) **CLAIM**

The ornamental design for a heel cup, as shown and described.

DESCRIPTION

FIG. 1 is a perspective view of a heel cup showing our new design;

FIG. 2 is a bottom plan view of a heel cup shown in FIG. 1;

FIG. 3 is a top plan view of a heel cup shown in FIG. 1;

FIG. 4 is a medial side view of a heel cup shown in FIG. 1;

FIG. 5 is a lateral side view of a heel cup shown in FIG. 1; and,

FIG. 6 is a back elevation view of a heel cup shown in FIG. 1.

All surfaces not shown form no part of the claimed design.

1 Claim, 4 Drawing Sheets
